UNITED STATES PATENT OFFICE

CAESAR RAVE, OF LUCKENWALDE, GERMANY

INCANDESCENT LAMP

Application filed August 9, 1930, Serial No. 474,185, and in Germany August 2, 1927.

This invention relates to incandescent lamps and more particularly to lamps having screw ferrules or "caps" of insulating material.

5 Its primary object is to produce an improved lamp of this type which will effect a reliable connection of the bulb with the screw ferrule.

To this end I secure an annular member of metal to the bulb of the lamp, and mount the insulating ferrule on this member.

Screw ferrules of insulating material are of course old, but have never been adopted because they could not be secured satisfactorily and permanently to the bulb by the usual cement, and because heat stresses occurred which damaged the ferrule, or the bulb, or both. Therefore the normal metal ferrules were again resorted to which are 20 readily cemented to the bulb and are not influenced by heat.

These difficulties are eliminated by my invention. In this the annular metal member which may be a ring, cylinder or sleeve, 25 or the like, is cemented to the bulb in the usual manner and affords a base for securing the insulating screw ferrule. Only the metal member is subjected to high temperature when the lamp is burning. This being the case, so that the insulating ferrule is not similarly heated, the selection of material for the same is not limited by temperature considerations. The ferrule may furthermore be comparatively weak as the 30 strength of the connection is provided by the metal member and not the ferrule. Therefore, paper and other light insulating materials may be used for the ferrule which involves another advantage. Heretofore, indications concerning the characteristics of the lamps, such as voltage, candle power, etc., have been stamped or etched on the ferrule, or else on the bulb. Such indications are usually very small or faint and difficult 35 to read, so that it is necessary to handle the lamp for inspection. Obviously, a lamp in a screw socket must be unscrewed from the socket to permit a reading of its indications.

50 All these inconveniences are eliminated

by using insulating ferrules of various colors to indicate the properties of the lamps. With caps of this kind the characteristics of the lamp, such as the voltage, wattage, candle power, etc., may be determined at a distance and without unscrewing the lamp from its socket.

I may additionally provide a flange on the insulating ferrule to abut against a corresponding flange on the socket, and also a packing washer inserted between the two flanges to protect the lamp from moisture, gas, etc.

In the accompanying drawing, three types of members and ferrules are illustrated by way of example.

Fig. 1 thereof is a section of a short annular member having hooked means for holding the ferrule.

Fig. 2 is a section of a long threaded annular member which is bent over at the upper end for holding the ferrule, and

Fig. 3 is a section showing a lamp socket combined with a member and ferrule as shown in Fig. 1, but with a flange on the ferrule.

In the several views, 1 denotes the bulb of the lamp, 6 the threaded insulating ferrule and 13 the central-contact cap or tip.

Referring first to Fig. 1, an annular member in the form of a cylinder 2 is shown secured to a seat on the upper end of the bulb 1 in this instance by a tapering lower end resting thereon with a layer of cement represented at 3 between. Tab-portions 4 and 5 of said member or cylinder extend upwardly through slots 7 and 8 in the ferrule 6 at opposite sides. The central-contact cap 13 is secured on the top of the ferrule, while the wire or wires 20 serve to supply the lamp filaments (not shown) with current.

After the cylinder 2 has been secured on the bulb 1, the insulating threaded ferrule 6 is fitted thereover with said tab-portions 4 and 5 projecting upwardly through its slots 7 and 8 as the tab-portion 4 appears in Fig. 1. These tab-portions are then bent downwardly over the slot edges into recesses 9 and 10 in the ferrule, as the tab-portion 5 is represented in Fig. 1, so that the ferrule will

be held against axial and radial displacement on the cylinder 2. When the lamp is screwed into the socket (not shown) the ends of the tab-portions bear against the threads of the socket to effect a good contact.

Referring now to Fig. 2, a cylinder 12 corresponding to that above described but not equipped with tabs is shown with portions 11 bent or doubled over at its upper end with the upper end of the ferrule within the bend. Said ferrule in this instance is threaded on both the outer and inner sides. The top of the ferrule may as shown be made as a separate part 14 which is screwed into the inner thread indicated at 15.

The insulating ferrule 6, which may consist of a plastic substance such as paper, cellulose, artificial rosin or the like, and the cylinder which fastens to the bulb are preferably connected with each other first and then threaded (including the bent portions 11) before the cylinder is secured on the bulb 1.

The ferrule affords excellent protection against touching contacts, as the contacting parts are arranged only in the upper end of the ferrule and make contact with other parts under voltage only after having been completely concealed in the holder socket. Only the lower end of the ferrule projects from the socket and it therefore prevents any touching of parts carrying current.

Referring now to Fig. 3, the ferrule 6 and the cylinder (not showing) are the same as in Fig. 1, except that the ferrule is provided with a flange 16 at its lower end. These parts are shown screwed into a threaded socket 19 within the usual shield or holder 17 preferably of insulating material, against the end of which said flange 16 of the ferrule is pressed. A packing washer 18 may be placed between them for protection against moisture or gas. The holder member may have or connect with a suspension eye 21 at its upper end and current conductor wires 22 for supplying the current may run through openings at its sides.

This holder or shield in the described construction prevents moisture or gas admission and at the same time relieves the delicate bulb of thrust from the pressure exerted on the washer 18. If the insulating ferrule is made of a bad conductor of heat, the washer 18 may be made of rubber, a material which cannot be used with metal ferrules as they become too hot.

As mentioned, the ferrule 6 may be coloured variously, as and for the purpose described. Its lower end, or the flange 16 in Fig. 3, is always exposed to view so that the characteristics of the lamp may be readily ascertained at a glance.

I claim:

1. In an incandescent lamp including a bulb, a screw-ferrule base comprising an an-

nular metal member having one end secured on the lamp bulb and an opposite end extension portion, and a threaded ferrule of an insulation material fitted over said member with the extension portion of the former bent over and down thereon providing current conductors bearing against the wall of the holder socket into which the same may be screwed.

2. A screw-ferrule base for incandescent lamps, comprising an annular metal member secured on the neck of the lamp, and a threaded insulation ferrule fitted over said member with a flexible portion of the former hooked over and down upon the same for holding it in place thereon and providing a current conductor bearing against the wall of a socket into which screwed; said ferrule having a flange for abutment against the end of the socket to exclude moisture and gas.

3. An incandescent lamp having an insulation screw-ferrule base comprising an annular metal member secured at one end on the neck of the lamp and having extension portions at its other end adapted to bending over, and a threaded ferrule of insulation material fitted over said member with one end bearing thereon against the lamp and with said extension portions of the member bent downwardly thereover at the other end so as to hold it in place and provide current conductors bearing against the walls of the socket member into which screwed.

4. In an incandescent lamp, a screw-ferrule base comprising an annular metal member secured on the lamp bulb and having axially extended portions adapted to bending, and a threaded ferrule of insulation material fitted over said member and having slot openings through which said axially extended portions of the member are passed and bent downwardly thereon for holding it in place and providing current conductors bearing against the walls of the socket into which the same is screwed.

5. In an incandescent lamp, a screw-ferrule base for securing in a holder socket, comprising an annular threaded metal member secured on the neck of the lamp and having axially extended portions adapted to bending over, and a threaded ferrule of insulation material applied over said member with the axially extended portions of the former bent over and partially down upon the same flush with the threading of its outer surface for holding it secure and providing contact against the wall of the socket into which screwed.

6. An incandescent lamp having an insulation screw-ferrule for securing in a holder socket, comprising an annular metal collar secured on the neck of the lamp bulb and having axially extended tab-portions adapted to bending over, and a threaded ferrule of

5 insulation material fitted over said member with said tab-portions of the member extending through slots therein and bent downwardly over the outer surface thereof into recesses so as to hold it in place and providing contacts bearing against the inner wall of the socket into which the same is screwed; said ferrule carrying a center contact cap on its outermost end.

10 7. In an incandescent lamp including a bulb, an insulated screw-ferrule base thereon, comprising an annular metal member secured on said bulb and a threaded ferrule of insulating material fitted over said member with tap-portions of the same bent over and

15 down thereon for holding it in place and providing current conductors bearing against the walls of the holder socket into which screwed.

20 8. In an incandescent lamp including a bulb, an insulating screw-ferrule base thereon comprising an annular metal member cemented on said bulb, a threaded insulating ferrule fitted over said member and a flexible 25 extension of said member hooked over an edge of the ferrule to hold it in place thereon.

30 9. A screw-ferrule base for an incandescent lamp, comprising an annular metal member secured on the lamp bulb and a threaded insulating ferrule fitted over said member with a flexible portion of the former hooked over and down upon the same for holding it in place thereon and providing a 35 current conductor bearing against the wall of a socket into which screwed.

In testimony whereof I affix my signature.
CAESAR RAVE.
